UNITED STATES PATENT OFFICE.

PETER HEINRICH FELIX SPIES, OF NEW YORK, N. Y., ASSIGNOR, BY DIRECT AND MESNE ASSIGNMENTS, OF ONE-THIRD TO DAVID E. AARONS, ONE-THIRD TO LEROY M. HANLON, AND ONE-THIRD TO WILLIAM T. LAMBERT, ALL OF NEW YORK, N. Y.

ELECTRIC SWITCH FOR STREET ARC-LAMPS, &c.

No. 810,857.

Specification of Letters Patent.

Patented Jan. 16, 1906.

Application filed February 10, 1905. Serial No. 245,047.

To all whom it may concern:

Be it known that I, PETER HEINRICH FELIX SPIES, a subject of the German Emperor, and a resident of the city of New York, borough 5 of the Bronx, in the county and State of New York, have invented a new and Improved Electric Switch for Street Arc-Lamps, Chandeliers, and the Like, of which the following is a full, clear, and exact description.

10 The object of the invention is to provide a new and improved electric switch more especially designed for street arc-lamps, chandeliers, and the like and arranged to keep the main-line circuit completely uninterrupted 15 whenever the lamp is cut out or lowered for the insertion of new carbons or for repairs or for other purposes, the lamp on being returned to its normal position being immediately and automatically cut in without interruption of the main-line circuit.

20 The invention consists of novel features and parts and combinations of the same, as will be more fully described hereinafter and then pointed out in the claims.

25 A practical embodiment of the invention is represented in the accompanying drawings, forming a part of this specification, in which similar characters of reference indicate corresponding parts in both views.

30 Figure 1 is a sectional side elevation of the improvement on the line 1 1 of Fig. 2, and Fig. 2 is a transverse section of the same on the line 2 2 of Fig. 1.

35 The hanger or casing for the electric-arc lamp is made in two parts A and B, of which the upper part A is suspended on a post, bracket, high ceiling, or other support and the lower part B carries the lamp and is raised or lowered by the usual rope or cable C under 40 the control of the operator employed for changing the carbons or for making repairs and the like.

45 In the upper or fixed part A of the hanger is secured a switch-block D, of hard rubber or other suitable insulating material, and on this switch-block D are secured sets of contacts E E, connected with line-wires F, the contacts E E being preferably in the shape of sets of contact-plates having downward and 50 upward extensions E' and E'', projecting beyond the bottom and top of the block D. The projecting ends E' of the contact-plates

E are adapted to be engaged by contacts G G in the form of pins and connected with the wires H of the circuit of the lamp hung on the 55 hanger part B, the said contact-pins G being fastened in a block I, made of an insulating material and secured by suitable brackets I' to the hanger part B, so that the block I and its contact-pins G move with the lamp.

60 The upper ends E' of the contacts E E are adapted to be engaged by auxiliary contacts K in the form of pins, connected with each other by a wire L and secured in a block N, made of insulating material, and provided 65 with guide-pins N', sliding in suitable bearings arranged in the contact-block D and adapted to rest at their lower ends on the upper surface of the block I, fixed in the hanger part B. The block N, carrying the auxiliary 70 contact-pins K, is pressed on in a downward direction by springs O, held in lugs A' on the hanger part A. The arrangement is such that when the part B is in a closed position, as illustrated in the drawings, then the contact-pins G are in engagement with the depending ends E' of the contacts E, so that the 75 line-wires F are connected with the lamp-wires H to allow the current to flow through the lamp. When the block I is in this uppermost position, it holds the block N raised against the tension of its springs O, so that the auxiliary contact-pins K are out of engagement with the upper ends E' of the contacts E.

80 When the operator lowers the hanger part B and the lamp hung thereon by manipulating the rope or cable C correspondingly, then the block I, and with it the contact-pins G, move out of engagement with the depending 85 ends E' of the contacts E; but during this downward movement of the block I the block N is forced in a like direction by the action of its springs O, so that the auxiliary contact-pins K move in engagement with the upper 90 ends E' of the contacts E previous to the auxiliary contact-pins G leaving the lower ends E' of the contacts E. Thus before the connection between the line-wires F and the lamp-wires H is broken the line-wires F are 95 connected with each other by way of the ends E' of the contacts E, the auxiliary pins K, and the connecting-wire L. When the 100 hanger part B is again raised to its normal

position, then the contact-pins G move in engagement with the depending ends E' of the contacts E, and at the same time the block I by acting on the pins N' lifts the block N, so that the auxiliary contact-pins K move out of engagement with the upper ends E² of the contacts E after the contact-pins G have made contact with the depending ends E' of the contacts E. Thus before the connection 10 of the line-wires F is broken by way of the auxiliary contact-pins K and their connecting-wire L the lamp-wires II are connected with the line-wires, so that the main-line current remains completely uninterrupted, whether 15 the lamp is in a raised normal position or is lowered for exchange of carbons, repairs, or other purposes.

It will further be seen that by the arrangement described the current is completely cut 20 off from the lamp while the latter is in a lowermost position, so that the operator can handle the lamp with the greatest safety—that is, without danger of receiving a shock 25 from the electric current.

25 The device is very simple and durable in construction and is composed of comparatively few parts not liable to easily get out of order.

Having thus described my invention, I 30 claim as new and desire to secure by Letters Patent—

1. An electric switch for arc-lamps, chandeliers, and the like, comprising fixed line-contacts connected with the line, a block 35 moving with the lamp and carrying lamp-contacts connected with the lamp-circuit, and adapted to engage the lower ends of the line-contacts, and a movable block carrying auxiliary contacts, electrically connected with 40 each other, the said block being controlled by the movement of the block carrying the lamp-contacts, the said auxiliary contacts being adapted to engage the upper ends of the line-contacts.

45 2. An electric switch for arc-lamps, chandeliers, and the like, comprising a fixed block, sets of contacts secured on said block and connected with the line, the contacts projecting beyond the bottom and top of the block, a 50 block movable with the lamp and carrying lamp-contacts connected with the lamp-circuit and adapted to engage the lower projecting ends of said line-contacts, and a movable block carrying auxiliary contacts, adapted to 55 engage the upper ends of said line-contacts, the movement of said block carrying the auxiliary contacts being controlled by the block carrying the lamp-contacts, the said auxiliary contacts being normally out of engagement 60 with the line-contacts.

65 3. An electric switch for arc-lamps, chandeliers, and the like, comprising a fixed block, sets of contacts secured on said block and connected with the line, the contacts projecting 70 beyond the bottom and top of the block, a

block moving with the lamp and carrying contacts connected with the lamp-circuits and adapted to engage the lower projecting ends of the said line-contacts, a block having guided movement and controlled by the 75 movement of the block carrying the lamp-contacts, the said block carrying auxiliary contacts adapted to engage the upper projecting ends of said line-contacts, the auxiliary contacts moving in contact with the 80 line-contacts immediately previous to the lamp-contacts moving out of engagement with the line-contacts.

4. An electric switch for arc-lamps, chandeliers, and the like, comprising a fixed block 85 of insulating material, sets of contact-plates secured on said block and connected with the line, the contact-plates projecting beyond the bottom and top of the block, a block of insulating material moving with the lamp and carrying contact-pins connected with the lamp-circuit, and adapted to engage the lower projecting ends of said line-contact plates, a block of insulating material provided with 90 guide-pins arranged to slide in bearings in the 95 said fixed block and adapted to rest on the upper surface of the block carrying the lamp-contact pins, the said block carrying auxiliary contact-pins electrically connected and adapted to engage the upper projecting ends of said line-contact plates, the movement of the block carrying the auxiliary contact-pins being controlled by the movement of the block carrying the lamp-contact pins, the said auxiliary contact-pins moving in contact 100 with the line-contact plates immediately previous to the lamp-contact pins moving out of engagement with the line-contact plates, and the said auxiliary contact-pins being moved out of engagement with the line-contact 105 plates after the lamp-contact pins have moved in engagement with the line-contact plates.

5. An electric switch for arc-lamps, chandeliers and the like, comprising a hanger 110 made in two parts, of which one is fixed and the other movable toward and from the fixed hanger part, the movable hanger part carrying the lamp, double line-contacts fixed in the said fixed hanger part and connected with 115 the line, a spring-pressed block carrying auxiliary contacts for engaging the line-contacts at one side, and a block fixed in the movable hanger part and carrying the lamp-contacts connected with the lamp-circuit, the said 120 lamp-contact block engaging the said spring-pressed block, to move the latter against the tension of its springs.

6. An electric switch for arc-lamps, chandeliers and the like, comprising a hanger 125 made in two parts, of which one is fixed and the other movable toward and from the fixed hanger part, the movable hanger part carrying the lamp, double line-contacts fixed in the said fixed hanger part and connected with 130

the line, a spring-pressed block carrying auxiliary contacts for engaging the line-contacts at one side, the said block having guide-pins 5
slidable in bearings on the said hanger part, and a block fixed in the movable hanger part and carrying the lamp-contacts connected with the lamp-circuit, the said lamp-contact block being adapted to engage the said guide-pins, to move the spring-pressed block against 10
the tension of its springs.

7. An electric switch for arc-lamps, chandeliers, and the like, comprising fixed line-contacts consisting of sets of contact-plates connected with the line, contact-pins moving 15
with the lamp and connected with the lamp-circuit, the said contact-pins being adapted to engage the line-contact plates, and auxiliary contact-pins controlled by the movement of the lamp-contacts and adapted to engage the 20
said line-contact plates.

8. An electric switch for arc-lamps, chandeliers, and the like, comprising a hanger made in two parts, one part being fixed and the other movable toward and from the fixed 25
part, the movable hanger part carrying the

lamp, a block secured to the upper or fixed part of the hanger, sets of contact-plates secured at each end of said block and having their ends projecting respectively beyond the bottom and top of the block, the said contact-plates being connected with the line-wires, a block secured to the movable hanger part, contact-pins carried by said block and connected with the lamp-circuit, the said contact-pins being adapted to contact with the 30
lower ends of said line-contact plates when the movable hanger part is in raised or normal position, and a spring-pressed block carrying contact-pins electrically connected with each other and adapted to contact with the upper 35
ends of said contact-plates when the movable hanger part is in the lowered position.

In testimony whereof I have signed my name to this specification in the presence of two subscribing witnesses.

PETER HEINRICH FELIX SPIES.
